207,500

LIGHT DIFFUSER

Lawrence P. Mellyn, Gloucester, R.I., assignor to General Electric Company, a corporation of New York

Filed June 21, 1966, Ser. No. 2,765

Term of patent 14 years

(Cl. D48—20)

FIG. 1

FIG. 2

FIG. 3

FIG. 4

FIG. 5

FIG. 1 is a front perspective view of a light diffuser embodying our new design showing the diffuser in relation to a night light base shown in phantom;

FIG. 2 is a front perspective view thereof as shown in separated condition from the night light base of FIG. 1;

FIG. 3 is a front elevational view thereof;

FIG. 4 is a side elevational view thereof; and

FIG. 5 is a back elevational view thereof.

The night light base shown in broken lines in FIGS. 1 and 2 is for illustrative purposes only.

I claim:

The ornamental design for a light diffuser, as shown and described.
